CLAIM

The ornamental design for a mounting plate, as shown and described.

DESCRIPTION

FIG. 1 is a front perspective view of a mounting plate depicting a new design;

FIG. 2 is a second front perspective view thereof;

FIG. 3 is a back perspective view thereof;

FIG. 4 is a front elevational view thereof;

FIG. 5 is a back elevational view thereof;

FIG. 6 is a left elevational view thereof;

FIG. 7 is a right elevational view thereof;

FIG. 8 is a top plan view thereof; and,

FIG. 9 is a bottom plan view thereof.

The broken line disclosures depicting a lighting fixture in FIG. 1 represent environmental structure that forms no part of the claimed design. The remaining broken line disclosures in the views represent portions of the mounting plate that form no part of the claimed design.

1 Claim, 5 Drawing Sheets
